PROCESS FOR REMOVING ASPHALTENES FROM CRUDE OIL

Everett N. Case, Homewood, Ill., assignor to Sinclair Refining Company, New York, N. Y., a corporation of Maine

Application October 27, 1951, Serial No. 253,509

2 Claims. (Cl. 196—39)

1

My invention relates to improvements in the refining of crude oil. More particularly, it relates to a method for treating the crude oil prior to conventional refining practices with a precipitating agent which selectively precipitates certain asphaltic constituents such as asphaltenes, metal contaminants, salt and like deleterious substances. My invention provides a simple and inexpensive method for improving the efficiency of conventional refining processes such as distillation and solvent extraction, for improving the effectiveness of catalytic cracking processes or conversely for making available increased supplies of suitable catalytic cracking charge stock, and for increasing the net available recovery of marketable oil per barrel of crude processed.

I have discovered that certain asphaltic constituents such as asphaltenes can be selectively precipitated from crude oil by contacting the crude with gaseous hydrogen chloride. The asphaltenes precipitate usually immediately on contact with the precipitating agent and may be separated from the crude by gravity settling, filtration or centrifuging.

Hydrogen chloride is soluble in crude oil to the extent of about 0.2 weight per cent. The per cent of asphaltenes precipitated appears to increase up to the point of saturation of the oil with the gas. I have found, however, that it is particularly advantageous to employ superatmospheric pressure, e. g. from about 15 to about 150-200 p. s. i. g. The per cent of asphaltenes precipitated then is greatly increased. The concentration of the precipitating agent thus may be regulated by pressure for particular crude oils which vary in asphaltic content or in content of metals and salt and which vary somewhat in solubility for hydrogen chloride. Ordinary temperatures should be employed. For example, I have found that operations at elevated temperature, e. g. 300° F., even with pressures of 50 to 150 p. s. i. g. result in reduced precipitation of asphaltenes. The effectiveness of the treatment is increased by mild agitation which assists in saturating the crude oil with the precipitating agent.

I have found that my invention is particularly applicable to crude oils which have not been subjected to desalting operation or which have not been topped by removal of light boiling distillate fractions. The desalting process seems to reduce the effectiveness of the agent in precipitating asphaltenes. Although treatment of topped crudes is technically feasible, the higher viscosity of the topped crude interferes with intimacy of contacting and effective saturation of the crude oil with the precipitating agent. Also, application of the treatment to topped crudes is disadvantageous in the sense that the heat put into the crude in the topping operation should be removed by cooling for effective asphaltenes precipitation, whereas thermal economics within the usual refinery

2

require conservation of heat by running the hot topped crude directly to succeeding distillation or cracking operations.

My invention will be further described with reference to the accompanying drawing which illustrates in simplified schematic form one means of application.

In the system of the drawing, crude oil is charged through line 10 to tank 11 which may be provided with a conical bottom. Advantageously, the tank is equipped with means for mildly agitating the crude oil contents. Hydrogen chloride gas is introduced at the bottom of tank 11 through line 12. Tank 11 is equipped with hydrogen chloride vent line 13 which runs into hydrogen chloride recycle line 14 and associated compressor 15 for recycling to tank 11. After saturation of the crude in tank 11 with hydrogen chloride gas under appropriate conditions of temperature and pressure, the treated crude is permitted to settle for a period of about 3 to 10 or 12 hours. The treated crude then is withdrawn from tank 11 by means of swing line 16 and connection 17 and charged to topping still 18.

Heat for the distillation process is provided by circulating oil from the bottom of still 18 through line 19 and heater 20 with return to the still 18 by means of connection 21. Hydrogen chloride is removed overhead from still 18 through line 22 and knock out drum 22a for return to the treating system by means of line 14. A slipstream of gas may be purged from the system through connection 23 if build up of fixed hydrocarbon gases tends to occur. Distillate fractions are removed as side streams at various levels of still 18 in the usual manner as indicated by connections 24, 25 and 26. Treated residual oil may be removed as bottoms through line 27.

Although I have shown only a single-tank treating and separating unit in the drawing, obviously the operations of my invention are facilitated by providing a plurality of tanks connected preferably to a common hydrogen chloride circulating system, in order to maintain continuous supply of treated crude to the crude oil distillation units. As noted above, the treating vessel advantageously is operated under superatmospheric pressure. I have found that pressures of about 15 to 50 p. s. i. g. hydrogen chloride are very effective. Higher pressures do not appear to increase materially the amount of asphaltenes precipitated. The amount of precipitating agent required is subject to variation with the nature of the crude oil to be treated and the temperature and pressure of the treatment, but I have found that about 0.1 to 0.9 pound of hydrogen chloride per barrel of crude oil is usually sufficient. In any event, it is advisable to provide at least enough of the precipitating agent to saturate the crude with the agent.

The principles of my invention will be further

illustrated in the following examples of treatments under various conditions:

Examples

The crude oil was charged to a vessel equipped with a mechanical agitator or to a vessel which could be shaken by hand. To the crude was added the specified amount of gaseous hydrogen chloride followed by agitation. The asphaltenes precipitated immediately and either collected on the walls of the vessel or were present as solid particles in the crude oil. The charge was removed from the vessel and centrifuged to remove the precipitate. The same end was attainable by about 12 hours' gravity settling. The clean crude layer was decanted and the precipitate was washed with straight run gasoline to remove the trapped crude. The wash liquid may be centrifuged or settled if necessary. The asphaltenes precipitate was weighed to determine yield. Where the precipitate adhered to the container walls, it was recovered by solution in benzene and the benzene was removed by distillation to give a residue of asphaltenes.

Using the above procedure the following tests were run on Mid-Continent crude which had been topped to 400° F. by removal of 31.5% overhead, increasing the density to 0.87:

Charge	Vol. HCl Gas	Wt. Percent Asphaltenes Yield
400 ml.	400	0.60
Do	800	1.87
Do	1,200	2.70
Do	1,600 (atmospheric saturation point)	3.88
700 ml.	50 p. s. i. g. HCl	7.23
Do	100 p. s. i. g. HCl	7.22
Do	150 p. s. i. g. HCl	7.12
Do	50 p. s. i. g. HCl at 300° F.	2.76
Do	150 p. s. i. g. HCl at 300° F.	3.56
Do	15 p. s. i. g. HCl	7.2±.2

In a similar test, the crude was first desalted. A charge of 700 ml. of density 0.808 was saturated with hydrogen chloride gas at 50 p. s. i. g. The weight per cent yield of asphaltenes amounted only to 2.1% or 2.78% when corrected to the 68.5% bottoms basis of the foregoing runs.

In a similar example, 700 ml. of untreated Poza Rica (Venezuela) crude oil of density 0.878 was saturated with hydrogen chloride gas at 50 p. s. i. g. The weight per cent yield of asphaltenes amounted to 6.92% or 9.10% corrected to a 68.5% bottoms basis.

After the crude oil was freed from the precipitate the dissolved hydrogen chloride was removed by the addition of straight run gasoline. The hydrogen chloride then was distilled off with the gasoline.

Mid-Continent crude was treated by saturation with hydrogen chloride at atmospheric pressure. After removal of the precipitate and precipitating agent in each case, the oil showed the following analyses compared to the untreated crude:

Crude	As Received	Precipitate	Residue
p. p. m. NiO	9.5	300	3.6
p. p. m. V ₂ O ₅	18.8	1,060	8

Hence the metals content of crude oil can be substantially reduced by application of my invention.

In another example, a topped Mid-Continent crude (69% bottoms) having a carbon residue of 3.0 weight per cent was treated by saturation

with hydrogen chloride gas. After removal of the hydrogen chloride, the carbon residue was 1.7%.

My invention provides a simple and inexpensive means for pretreating crude oil prior to conventional refinery processing. Removal of a substantial proportion of the asphaltic constituents of the crude before the oil is subjected to thermal processing such as cracking, vis-breaking or vacuum distillation increases significantly the yield of the more valuable oil fractions per barrel of crude processed. The net production of coke or asphalt is reduced and thereby reduces significantly the amount of low value residuum which must be disposed of in the form of heavy fuel oils or asphalt. About 40 to 60% of the content of solid asphalt represents valuable heavy oil constituents which are normally lost. My invention thus increases potential oil recovery in proportion to the reduction in asphalt residuum. Also disposal of the heavy residuum as fuel oil requires expenditure of considerable amounts of distillate oil as cutter stock. Any decrease in the amount of residuum therefore conserves oil by reducing the requirements for cutter stock.

One of the limiting factors on utilization of heavy gas oil stocks as charge to catalytic cracking units is the carbon residue of the charge stock which deleteriously affects product distribution in the cracking reaction and reduces capacity of the unit by increasing the burden on the coke-burning capacity of the catalyst regeneration equipment. Application of my invention permits utilization of heavier gas oil stocks without deleteriously affecting product distribution and without overburdening the coke-burning capacity of the catalytic cracking unit. Application of my invention is of further value in promoting the economics of catalytic cracking by reducing substantially the metals content of the cracking charge stocks. The result is improved catalyst life and a substantial reduction in the rate at which catalyst must be discarded from the unit to maintain a desired equilibrium activity level.

In lubricating oil refining and production, application of my invention facilitates deasphalting and solvent extraction operations and results in improved raffinate yields.

I claim:

1. A method for removal of asphaltenes and metal contaminants from crude oil prior to desalting and conventional refining procedures which comprises saturating the crude at a pressure from 15 to 200 pounds per square inch gauge with a precipitating agent consisting of gaseous hydrogen chloride and separating the agent and precipitated matter from the treated crude.

2. A method of removal of asphaltenes and metal contaminants from crude oil prior to desalting and conventional refining procedures which comprises saturating the crude at a pressure from 15 to 200 pounds per square inch gauge with gaseous hydrogen chloride, separating precipitated matter from the treated crude and recovering hydrogen chloride from the treated crude by distillation.
